19 Claims. (Cl. 242—58)

1

The present invention relates to reels for web fed rotary printing presses and more particularly to an improved paper reel construction of the rotary multi-spindle type wherein a plurality of paper roll supporting spindles are carried in circumferentially spaced positions about the common central axis of a rotatable spool-like reel assembly and are supported by radially extending spider arms which project outwardly from the ends of the reel assembly.

Paper reel mountings of the type briefly outlined above are commonly employed at the loading zone of large web fed rotary printing presses and usually they have spindle supports to accommodate three paper rolls arranged 120° apart and including the actual feeding paper roll, the axis of which during the normal run of the press, is situated at and extends generally in the horizontal plane of the central reel assembly supporting shaft; a reserve paper roll, the axis of which, during the normal run of the press, assumes a position above the horizontal plane of the central shaft and at the other side thereof; and a freshly loaded paper roll, the axis of which assumes a position at a loading station or location directly beneath the axis of the reserve paper roll and on the same side of the central shaft as the latter. Paper reel constructions of this character are generally known as three-arm spider reel assemblies, and these assemblies are capable of being indexed through 120° of rotation periodically to advance each spindle to the position occupied by its predecessor so that the expiring feeding roll may be brought to the loading station, the reserve roll brought into operative feeding position; and the freshly loaded roll brought to the reserve position.

Paper reel constructions of this type are ordinarily indexed by means of an indexing, driving or spur gear which meshes with a larger gear carried by one of the reel spiders. This spur driving gear not only serves to perform the periodic indexing operations of the reel assembly but also, during the normal run of the press, serves as a reaction member which absorbs any existing torque applied to the reel shaft by virtue of the unbalanced weight of the loaded reel spindles, thus holding the entire spool-line paper reel assembly stationary in any of the three indexed positions of which the same is capable of assuming.

In constructions of this character, the change that takes place in the unbalanced weight of the reel assembly as a whole is considerable, whether this change occurs as a result of the progressive feeding of the web from the feeding roll, or whether it takes place as a result of indexing of the reel assembly and consequent shifting of the centers of the loaded or unloaded paper spindles about the central axis. Such changes in the torque load acting upon the reel

2

supporting shaft set up torsional stresses and consequent torsional deformation of the central shaft which are relatively great when it is considered that the weight of a full length paper roll may be as much as two thousand pounds. The net effect of such changes in torsional deformation of the central shaft is to set up corresponding changes in the alignment of the paper feed roll whereby one end thereof will 10 "sag," so to speak, and cause spindle misalignment. A large component of the misalignment of the paper roll takes place in a plane parallel to the lead of the paper web in such a manner that the tensional forces existing in the web are concentrated along one edge thereof and are conducive toward frequent web rupture.

Further changes in misalignment of this character tending to concentrate the tensional forces of the web along one edge thereof may take place by virtue of manufacturing tolerances in the fitting of the spiders to the central reel shaft and principally by virtue of existing looseness in the key by means of which the parts are operatively connected together for rotation in unison. Not only are such changes accentuated additively as any particular paper roll passes over its dead center position with respect to the central shaft, but also such changes are accentuated by the mechanical advantages possessed by each roll spindle due to its offset position which is farther removed from the axis of the central shaft than is the offset position of the key.

Heretofore one method that has been employed 35 in an effort to compensate for web misalignment has been the provision of a so-called "cocking roller" on the printing press which is capable of having one end thereof adjusted in a plane perpendicular to the lead of the web after the 40 same has left the cocking roller. Thus if the lead of the web leaving the cocking roller is substantially horizontal, as frequently is the case, provision is made for adjusting one end of the cocking roller in a vertical plane. The use 45 of a cocking roller of this character has proven to be only a partial remedy in compensating for web misalignment inasmuch as the roller can be adjusted only to compensate for misalignment of the paper feed roll when the supporting spider arms therefor are substantially horizontal and 50 when the paper roll is of full diameter. When the spider arms are indexed away from their horizontal position, the shifting of the forces acting upon the central reel supporting shaft renders the pre-adjusted position of the cocking roller 55 considerably in error while additionally the diminishing weight of the expiring paper feed roll further effects a gradual change in the misalignment of the roll which is at variance with the predetermined setting of the cocking roller.

The present invention is designed to overcome

the above noted limitations that are attendant upon the use of cocking rollers and other expedients for compensating for the changing misalignment of paper feed rolls at the loading zone of a printing press. Accordingly, it is among the principal objects of the present invention, in a reel of the character set forth above, to provide means for completely eliminating the factor of manufacturing tolerances from considerations of paper feed roll alinement.

Another and equally important object of the invention is to provide a paper reel construction of this character having associated therewith means for effectively compensating for torsional deformation of the reel supporting shaft in such a manner that, despite such deformation, the paper feed roll will remain substantially parallel with the axis of the receiving or cocking roller of the printing press in all indexed or intermediate positions of the reel assembly and regardless of the amount of paper web which has been spun from the paper feed roll.

A still further object of the invention is to provide such a paper reel construction in which the compensating means, both for changes existing by virtue of manufacturing tolerances, or for changing torsional deformation of the paper reel assembly supporting shaft, are wholly contained within the reel construction or assembly itself. Stated in other words, it is an object of the invention to provide a paper reel assembly of this sort having associated therewith "built in" compensating means for correcting any tendency for misalignment of the paper feed roll during operation of the printing press.

Another object of the invention is to provide a compensating paper reel construction of the character set forth above in which the means supporting the actual paper feed roll are self-aligning during feeding of the printing press from the paper roll so that no manual alining operations involving a cocking roller are required during this period.

Yet another object of the invention is to provide a paper reel construction of this sort which may be manufactured in its entirety or which, alternatively, may be constructed by slight modification of existing paper reel constructions.

The provision of a paper reel construction which is extremely rugged and durable; one which may be manufactured at a relatively low cost; one which is comprised of a minimum number of relatively moving parts and which consequently is unlikely to get out of order; one which may be readily disassembled for purposes of inspection, repair, or replacement of the working parts thereof; one which requires little or no attention when in use; and one which otherwise is well-adapted to perform the services required of it are further desiderata that have been borne in mind in the production and development of the present invention.

This application is a continuation in part of the copending application of Henry L. McWhorter, Serial No. 222,136, filed April 20, 1951, and now abandoned in favor of this application.

In the accompanying drawings:

Figure 1 is a fragmentary side elevational view, partially schematic in its representation, of a conventional three-arm spider paper reel construction illustrating the manner in which deflection between the spiders takes place due to torsional deformation of the reel shaft when loaded.

Fig. 2 is a side elevational view similar to Fig. 1

and likewise schematic in its representation illustrating the manner in which torsional deformation of the reel shaft is compensated for according to the present invention.

Fig. 3 is an end elevational view partly in section of the reel construction shown in Fig. 2.

Fig. 4 is an enlarged sectional view taken substantially along the line 4-4 of Fig. 3.

Fig. 5 is a sectional view taken substantially along the line 5-5 of Fig. 4.

Fig. 6 is a sectional view taken substantially along the line 6-6 of Fig. 4.

Fig. 7 is a sectional view taken substantially along the line 7-7 of Fig. 3.

Fig. 8 is a graph representing certain spindle misalignment normally encountered in connection with three-arm spider reel assemblies and also representing the manner in which compensation therefor is effected according to the present invention.

Fig. 9 is an end elevation of a modified embodiment of the invention.

Fig. 10 is a side elevational section of the modified embodiment taken generally along the line 10-10 of Fig. 9, and

Fig. 11 is an elevational section taken generally along the line 11-11 of Fig. 9, to show the hub construction of the gear end spider shown in Figs. 9 and 10.

In all the above described views, similar characters of reference are employed to designate similar parts throughout.

While the invention is susceptible of various modifications and alternative constructions, there is shown in the drawings and will herein be described in detail the preferred embodiments, but it is to be understood that it is not thereby intended to limit the invention to the forms disclosed, but it is intended to cover all equivalents, modifications and alternative constructions falling within the spirit and scope of the invention as expressed in the appended claims.

Referring now to the drawings in detail and in particular to Fig. 1, wherein a conventional paper reel construction of the three-arm spider type as outlined above has been illustrated, the reel assembly is mounted upon a central supporting shaft 10, hereinafter referred to as the "reel shaft" which is rotatably journaled at its ends in side frames or standards 12 and 14 (see also Fig. 3) forming part of the stationary printing press framework 16. The reel assembly, in addition to the shaft 10, involves in its general organization a pair of roll supporting means in the form of end spiders including a spider 18, hereinafter referred to as the "gear side" spider, and a spider 20, hereinafter referred to as the "free end" spider, each spider having three radially extending spider arms 22 of substantially identical construction arranged 120° apart. In the position of the reel assembly shown in Fig. 1, one pair of spider arms labeled with the letter 7 extends downwardly at an angle of approximately 30° from a vertical plane passing through the axis of the shaft 20 so that these arms exist in loading position wherein a roll *p* of paper may be applied thereto at a loading station *s*. Another pair of spider arms 22, labeled *r* extend upwardly and are inclined at approximately 30° from the vertical plane of the shaft 10 and are adapted to support therebetween a reserve paper roll *p* in what is termed herein as the reserve position. The third pair of spider arms, labeled *f*, extend outwardly at an angle of substantially 90° from the vertical plane of the shaft 10 and are adapted to

support therebetween a third paper roll p in feeding position so that a web w of the paper in the roll may be fed from the roll to the first roller 24 of the printing press.

The spider arms 22 serve to support roll center supporting elements in the form of spindles 26, suitable means (not shown) being provided for enabling these spindles to be withdrawn from the rolls for the purpose of removing the cores of expired rolls and mounting fresh rolls of paper on the reel at the loading station s .

The shaft 10 carries at one end thereof a relatively large driving or indexing gear 28 which is adapted to mesh with a smaller driving gear 30 by means of which the spider assembly may periodically be indexed in a clockwise direction, as viewed in Fig. 1, throughout an angle of 120° to bring a freshly loaded paper roll p at the loading station s to a reserve position wherein its supporting spiders extend upwardly at an angle of 30° from the vertical; to bring the reserve paper roll p from the reserve position to the feeding position wherein its supporting spider arms extend 90° from the vertical; and to bring an expiring paper roll p from feeding position to loading position at the loading station s .

Since the operative drive for the central reel shaft 10 is obtained at one end of the shaft only, and exists by virtue of the driving gear 30, this gear not only serves to perform the periodic indexing operations of the reel assembly but also, during the normal run of the press, serves as a reaction member which absorbs any existing torque applied to the reel shaft and therefore holds the paper reel assembly stationary in any of its three indexed positions.

With the shaft 10 thus held against rotational movement by virtue of the gears 28 and 30 on the gear end of the shaft, there will be a certain amount of lateral or downward deflection of the far end spider arm labeled f in the feeding position, by virtue of torsional stresses that are applied to the shaft 10 due to the unbalanced weight of the paper rolls p on the various spindles 26. This deflection may be described as a sagging of the far or free end spider 20 as viewed in Fig. 1. The deflection between the uncompensated position of the arm f of the gear side spider and the position of the arm f of the free end spider has been illustrated in Fig. 1 by the angle θ . This angle represents the amount of torsional deflection of the section of the shaft 10 existing between the two spiders and it is proportional to the length of the paper roll p supported upon the spindle 26 between the two spiders. The amount of torsional deflection represented by the angle θ is also proportional to the unbalanced weight of the paper rolls which likewise is proportional to the length of a paper roll. Therefore, the torsional deflection of the section of the shaft existing between the two spiders is proportional to the square of the paper roll length.

The deflection as represented by the angle θ in Fig. 1 will vary for different paper roll mountings as well as for different paper roll lengths, but the disclosure of the drawings has been made on the basis of a full length roll. In such instances, the spiders 18 and 20 will occupy positions widely spaced on the central reel shaft 10 and near the ends thereof. Provision is made, however, for the accommodation of fractional length paper rolls such as half and quarter rolls. These rolls may be positioned on the reel assembly at any desired transverse location and the two spiders 18 and 20 may be adjusted along the

shaft 10 to the proper positions for effective spindle support.

The angle θ illustrated in Fig. 1 is not only representative of the torsional deflection of the length of the shaft 10 existing between the two spiders 18 and 20 but it also is inclusive of a misalignment between the two spiders that occurs as the result of manufacturing tolerances in the fit of the spiders on the reel shaft key 32. This discrepancy, existing near the center of rotation of the reel assembly, is materially magnified at the region of eccentricity of the spindles 26 by virtue of the mechanical advantage possessed by the spindles due to their further offset position. The mechanical advantage of the spindles 26 over the key 32 is approximately 7:1 and the resultant misalignment due to manufacturing tolerances is therefore seven times the difference in the tolerances of the two spiders on the key. This misalignment is accentuated additively as each paper roll spindle passes over its dead center position thus throwing the weight of the paper roll from one side of the vertical longitudinal plane of the shaft to the other side thereof.

In Figs. 3 to 6, inclusive, a preferred means for compensating for the deflection between the two spiders 18 and 20 is illustrated. Briefly, the factor of manufacturing tolerance is completely eliminated by the expedient of tightening the free end spider casting to the elongated key 32 with set screws that extend into the sides of the key instead of into the outer face of the key, while compensation for the rotational deflection of the reel shaft 10 is effected by elastically mounting the gear side spider on the reel shaft so that the spider may yield to an extent substantially commensurate with the amount of torsional deflection of the reel shaft 10, all in a manner that will now be more fully described.

As shown in Fig. 7, the hub 34 of the free end spider 20 is provided with a keyway 33 designed for reception thereon of the key 32. A plurality of pairs of alined bores 35 projecting through the hub 34 communicate with the keyway 33 and a plurality of set screws 36 threadedly received in the bores 35 are adapted to have their ends abut against the sides of the key 32 to effectively prevent angular turning movement of the spider 20 as a whole relative to the free end of the shaft 10. One of these set screws 36 may be brazed in position as indicated after initial adjustment thereof.

The spider casting 18 is provided with a keyway 36 (Fig. 6) for reception of the shaft key 32. This keyway 36 is somewhat wider than the standard keyway employed in connection with the construction in Fig. 7 so that a clearance 39 (Fig. 6) is provided between the casting and key on opposite sides of the latter. Thus the spider casting is capable of limited angular movement on the shaft 10. A torque collar 38 (Fig. 4) having a sleeve portion 41 and a radially extending flange 40 at one end thereof is mounted on the shaft 10 and occupies a position in close proximity to the spider 18 and is secured to the latter through the medium of yieldable spring means in the form of an elastic torque transmitting sleeve member 42 the nature of which will be made clear presently.

The sleeve portion of the torque collar 38 is provided with a plurality of pairs of alined threaded bores 44 (Fig. 5) which communicate with a keyway 46 formed in the sleeve. The keyway 46 is slightly greater in width than the width of the key 32 so that clearance space 48

is provided on each side of the key when the collar is in position on the shaft 10. Set screws 50 threadedly received in the bores 44 are adapted to bear at their inner ends against the sides of the key 32 so that the collar 38 is firmly held against angular turning movement with respect to the portion of the shaft 10 on which it is mounted.

The sleeve member 42 is provided with an inner radially extending flange portion 52 and a similar outer radially extending flange portion 54. The flange portion 52 is secured to the outer hub 56 of the spider 18 by means of a series of circumferentially spaced studs 58 while the flange 54 is secured to the flange 40 of the torque collar 38 by means of a similar series of circumferentially spaced studs 60. The length of the elastic sleeve member 42 may be slightly greater than the distance between the inner face of the flange 40 and the outer face of the hub 56 so that a slight clearance such as is shown at 62 (Fig. 4) is provided between the inner end of the torque collar and the outer face of the hub. The elastic sleeve member 42 is preferably formed of hardened spring steel and a series of longitudinally extending elongated slots 64 (Figs. 3 and 5) are provided in the medial regions of the sleeve between the two flanges 52 and 54, the slots defining therebetween a series of parallel extending struts 66 which are adapted to yield or flex in a circumferential direction to an extent which is directly proportional to the amount of torque applied to the flange 52 by the hub 56 when torsional deformation of the reel shaft 10 and consequent misalignment between the spider 20 and a fixed reference point on the shaft 10 occurs.

Referring now to Fig. 2, the axis X—X represents the horizontal plane of a fixed imaginary reference point provided on the shaft 10, which reference point for convenience has been shown as being the center line of the key 32. The axis Y—Y represents the deflection of the arm f of the spider 20 relative to this fixed reference point due to torsional deflection of the shaft 10 with two of the paper rolls p mounted on the reel assembly and in the reserve and feeding positions respectively. Due to the angular yieldability of the spider 18 existing by virtue of the flexible mounting therefor just described, the axis Y—Y also indicates approximately the angular deflection of the arm f of the spider 18. Thus, the two arms f of the spiders 18 and 20 respectively are substantially in coincidence so that the web roll supported therebetween is substantially horizontal.

The manner in which such compensation for torsional deflection of the central reel shaft takes place will be clear from the above description when considered in connection with the graph of Fig. 8. However, in this graph a more extreme condition is portrayed wherein two paper rolls are installed on the reel assembly with the supporting spindles 26 therefor disposed in the loading and reserve positions respectively. Such a condition is a normal one and would exist immediately prior to a pasting operation with the roll at the feeding position substantially expired.

In the graph of Fig. 8, the horizontal abscissae represent the width of the web undergoing feeding to the printing press, or correspondingly, the width of the paper rolls mounted on the reel assembly. The vertical ordinates represent spindle misalignment or the difference in spindle deflection between the spiders 18 and 20 (Figs. 1 and 2), in thousandths of an inch. The curved graph 75

line represents spindle deflection at the free end spider 20 for different lengths of paper rolls, due to torsional deflection of the shaft 10 and corresponding angular deflection of the spider 20, relative to the uncompensated position of the spider 18. This is a measure of the deflection between the two spiders that would normally occur in the absence of the elastic mounting for the gear side spider 18.

10 The straight graph line represents spindle deflection at the gear side spider 18 for the different lengths of paper rolls, when the gear side spider 18 is permitted the restricted movement afforded it by the elastic mounting of the present invention. The distance between points on the 15 two lines along the same ordinate represents any uncorrected spindle misalignment that may remain after the gear side spider has been moved angularly under the influence of the elastic 20 mounting.

The zero ordinate point indicates that with no paper on the spindles there would be no torsional deflection of the shaft 10 and consequently no discrepancy between the positions of the two

25 spiders 18 and 20. With approximately 34 inch, or half width paper rolls mounted on the reserve and loading spindles 26, the spindle deflection at the free end spider 20 is approximately .011 inch while the spindle deflection at the gear side spider

30 is approximately .017 inch. Thus the actual spindle misalignment is only .006 inch and this misalignment is sufficiently small that it may be disregarded as a factor of web misalignment. With half width rolls thus mounted on the spindles

35 and with the extreme condition outlined above, the maximum spindle misalignment that may be expected at any time takes place. This negligible misalignment is the result of overcorrection by the elastic mounting of the gear side spider.

40 With three-quarter width rolls of approximately 51 inches, spindle misalignment is approximately .002 inch and with paper widths of approximately 56 inches, complete coincidence between lines of the graph indicates that perfect correction takes place so that no spindle misalignment exists.

45 For full width rolls of approximately 68 inches, the spindle deflection at the free end spider 18 is at a maximum of approximately .039 inch while spindle deflection at the gear side spider 18 is approximately .034. Thus there is a slight undercorrection of approximately .005 inch which, for practical purposes in paper web feeding, is negligible.

50 From the above description it will be seen that the linear correction afforded by the elastic mounting for the gear side spider 18 cannot completely compensate for the quadratic deflection of the free end spider 20 except for a particular paper roll width. However, the maximum misalignment that may be expected is sufficiently small as

60 to present no problem in web feeding operations and, as a consequence, the present invention provides a means for maintaining the web rolls at all times in substantial alignment with the first receiving roller of the printing press within tolerable limits.

65 The disclosure of the invention made herein has not considered the factor of beam deflection wherein deflection of the reel shaft 10 as a beam becomes a consideration. It is worth mentioning, however, that in certain centrally offset positions of fractional width paper rolls along the supporting central shaft 10 there is a deflection of the central shaft 10 when considered as a beam which additively applies a fixed deflection to the

entire shaft and spider assembly. This beam deflection may readily be corrected by the provision of a cocking roller on the printing press which is set permanently for that particular lateral position of the spiders to compensate for the fixed amount of deflection. A relatively small amount of torsional deflection takes place in the shaft 10 in that section thereof existing between the gear 28 and torque collar 33. Due to the fact that this deflection causes no relative deflection between the two spiders 18 and 20 it has not been considered in the present disclosure.

All other discrepancies in alignment of the paper feed spindle except those just mentioned above are satisfactorily compensated for by the present invention.

Figs. 9, 10, and 11 illustrate a modified embodiment of the invention, comprising a paper reel 70 which is similar in some respects to the reel shown in Figs. 1-8. Thus the shaft 10, the press framework 16, the free end spider 20, the roll spindles 26, and the gear 28 remain unchanged in the modified reel 70. The outer ends of the paper rolls are supported by the free end spider 20, which is rigidly mounted on the shaft 10 near its outer end. Because of the torsional compliance or elasticity of the shaft 10, the weight of the paper rolls and the pull of the web produce an angular deflection of the spider 20 relative to the gear 28. This deflection would result in skewing of the paper rolls, if left uncompensated, and would tend to cause breaks in the web.

As in the first embodiment, however, the inner ends of the paper rolls are provided with elastic supporting or spring means having a torsional compliance corresponding generally to the torsional compliance of the reel shaft 10. In the embodiment of Figs. 9-11, the supporting means comprises a modified gear end spider 72 which replaces the gear end spider 18 and the elastic coupling 42 of the first embodiment. The spider 72 incorporates torsional spring means, taking the form of compliant radial arms 74 (Fig. 10) which are substantially thinner than the arms 22 of the free end spider 20. At their outer ends, the arms 74 support the roll center supporting elements or spindles 26. A hub 76 is formed integrally with the arms 74 for rigidly securing the latter to the reel shaft 10. As shown in Fig. 11, the hub 76 comprises a keyway 78 formed therein for receiving the key 32, together with a pair of set screws 80 engageable with the side of the key. To provide for a small amount of angular adjustment of the spider 72 on the shaft 10, the keyway 78 is made substantially wider than the key 32.

Because of their relatively light construction, the arms 74 deflect slightly under the weight of the paper rolls. For a particular spacing of the spiders 20 and 72 along the shaft 10, the torsional compliance of the arms 72 is equal to the torsional compliance of the portion of the shaft between the spiders, so that exact compensation is provided for the angular deflection of the shaft. As fully explained in connection with the first embodiment, a slight but insignificant overcompensation is obtained when the spiders are moved closer together to accommodate narrow rolls, while a slight undercompensation results from spreading the spiders to handle wide rolls. As a practical compromise, the elasticity of the spider 72 may be such as to afford exact compensation when the spacing between spiders is

such as to accommodate 56 inch rolls, which would be slightly wider than standard three-quarter width rolls.

The second embodiment is extremely simple in construction and low in cost, since an elastic spider can be manufactured nearly as easily and economically as an ordinary rigid spider. Moreover, a conventional uncompensated paper reel may be converted into a compensated reel, embodying this invention, merely by replacing the usual rigid gear end spider with an elastic spider, without otherwise modifying the reel.

I claim as my invention:

1. A reel assembly for printing presses comprising a central supporting shaft mounted for rotation about a horizontal axis, a pair of radially extending supporting arms mounted on said shaft in spaced relationship, roll supporting elements carried at the outer ends of said arms for receiving thereon a paper roll, means for applying torque to one end of said shaft to index the shaft and move the roll from a loading position to a feeding position wherein the roll assumes a position offset from the vertical plane of the axis of said shaft, means for securing one of said arms to said shaft against turning movement relative thereto, and yieldable means for securing the other arm to said shaft while permitting limited angular deflection of the arm relative to the shaft at its region of attachment substantially in proportion to the force exerted upon said latter arm through said roll supporting element thereon by said paper roll.

2. A reel assembly for printing presses comprising a central supporting shaft mounted for rotation about a horizontal axis, a pair of radially extending supporting arms mounted on said shaft in spaced relationship, roll supporting elements carried at the outer ends of said arms for receiving thereon a paper roll, means for applying torque to one end of said shaft to index the shaft and move said roll from a loading position to a feeding position wherein the roll assumes a position offset from the vertical plane of the axis of said shaft, means for securing one of said arms to said shaft against turning movement relative thereto, and yieldable means for securing the other arm to said shaft while permitting limited turning movement of the arm relative to the shaft substantially in direct proportion to the unbalanced torque of said other arm.

3. A reel assembly for printing presses comprising a central supporting shaft mounted for rotation about a horizontal axis, a pair of spiders each having a plurality of radially extending supporting arms formed thereon mounted on said shaft at opposite ends thereof, said arms being arranged in substantially aligned pairs, roll supporting elements adapted to receive a paper roll thereon carried at the outer ends of said arms, means for applying torque to one end of said shaft to index the shaft and move said roll supporting elements successively through loading, reserve and feeding positions, means for fixedly securing one of said spiders to one end of said shaft against turning movement with respect to said end, and yieldable means for securing the other spider to the other end of said shaft while permitting limited turning movement thereof relative to said latter end substantially in proportion to the torque exerted upon said latter spider through said roll supporting elements by the paper rolls mounted thereon.

4. A reel assembly for printing presses comprising a central supporting shaft mounted for

11

rotation about a horizontal axis, a pair of spiders each having a plurality of radially extending supporting arms formed thereon mounted on said shaft at opposite ends thereof, said arms being arranged in substantially aligned pairs, roll supporting elements adapted to receive paper rolls thereon carried at the outer ends of said arms, means for applying torque to one end of said shaft to index the shaft and move said roll supporting elements successively through loading, reserve and feeding positions, means for fixedly securing one of said spiders to the other end of said shaft against turning movement with respect to said latter end, and yieldable means for securing the other spider to the first specified end of said shaft while permitting limited turning movement thereof relative to said first specified end substantially in proportion to the torque exerted upon said latter spider through said roll supporting elements by the paper rolls mounted thereon.

5. A reel assembly for printing presses comprising a central supporting shaft mounted for rotation about a horizontal axis, a pair of spiders each having a plurality of radially extending supporting arms formed thereon mounted on said shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing one of said spiders to the other end of said shaft against turning movement with respect to said latter end, a torque collar fixedly mounted on said shaft adjacent the other spider, and elastic means for securing said torque collar to said latter spider to permit limited turning movement of said latter spider relative to said torque collar substantially in proportion to the torque exerted upon said latter spider through said roll supporting elements by the paper rolls mounted thereon.

6. A reel assembly for printing presses comprising a central supporting shaft mounted for rotation about a horizontal axis, a pair of spiders each having a plurality of radially extending supporting arms formed thereon mounted on said shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing one of said spiders to the other end of said shaft against turning movement with respect to said latter end, a torque collar fixedly secured to said shaft adjacent the other spider and on the side thereof remote from said fixedly secured spider, and elastic means connecting said torque collar to said other spider while permitting limited turning movement thereof relative to the torque collar substantially in proportion to the torque exerted upon said latter spider through said roll supporting elements by the paper rolls mounted thereon.

7. A reel assembly for printing presses comprising a central supporting shaft mounted for rotation about a horizontal axis, a pair of spiders each having a plurality of radially extending supporting arms formed thereon mounted on said

12

shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing one of said spiders to the other end of said shaft against turning movement with respect to said latter end, a torque collar fixedly secured to said shaft adjacent said other spider on the side thereof remote from said fixedly secured spider, and a series of elastic struts secured at one end to said torque collar and at the other end to said other spider and constituting yieldable means for securing said other spider to the torque collar while permitting limited turning movement thereof relative to the torque collar.

8. A reel assembly for printing presses comprising a central supporting shaft mounted for rotation about a horizontal axis, first and second spiders each having a plurality of radially extending supporting arms formed thereon mounted on said shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing the first spider to the other end of said shaft against turning movement with respect to said end, a torque collar secured to said shaft adjacent the second spider, and elastic means operatively connecting the second spider and torque collar and permitting limited yieldable turning movement of the second spider relative to the torque collar substantially in proportion to the torque exerted upon said latter spider through said roll supporting elements by the paper rolls mounted thereon.

45. 9. A reel assembly for printing presses comprising a central supporting shaft mounted for rotation about a horizontal axis, first and second spiders each having a plurality of radially extending supporting arms formed thereon mounted on said shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing the first spider to the other end of said shaft against turning movement with respect to said end, a torque collar secured to said shaft on the side of said second spider remote from said first spider, and a series of elastic struts connected at one end to said torque collar and at the other end to said second spider, said struts permitting limited turning movement of said second spider on said shaft.

10. A reel assembly for printing presses comprising a central supporting shaft mounted for rotation about a horizontal axis, first and second spiders each having a plurality of radially extending supporting arms formed thereon mounted on said shaft at opposite ends thereof, said arms being arranged in substantially aligned pairs, a plurality of roll supporting elements

adapted to receive paper rolls thereon carried at the outer ends of said arms, means for applying torque to one end of said shaft to index the shaft and move said roll supporting elements successively through loading, reserve and feeding positions, means for fixedly securing the first spider to the other end of said shaft against turning movement with respect to said end, a torque collar secured to said shaft on the side of said second spider remote from said first spider, an elastic spool-like torque member capable of torsional deformation and formed of yieldable resilient material having an elastic limit above the limit of torque normally applied to said second spider through said spindles by the paper rolls mounted thereon, said spool-like member having a sleeve-like medial region provided with end flanges, means for securing one of said end flanges to said torque collar, and means for securing the other end flange to the second spider.

11. A reel assembly for printing presses comprising a central supporting shaft mounted for rotation about a horizontal axis, first and second spiders each having a plurality of radially extending supporting arms formed thereon mounted on said shaft at opposite ends thereof, said arms being arranged in substantially aligned pairs, a plurality of roll supporting elements adapted to receive paper rolls thereon carried at the outer ends of said arms, means for applying torque to one end of said shaft to index the shaft and move said roll supporting elements successively through loading, reserve and feeding positions, means for fixedly securing the first spider to the other end of said shaft against turning movement with respect to said end, a torque collar secured to said shaft on the side of said second spider remote from said first spider, an elastic spool-like torque member capable of torsional deformation and formed of yieldable resilient material having an elastic limit above the limit of torque normally applied to said second spider through said spindles by the paper rolls mounted thereon, said spool-like member having a sleeve-like medial region provided with end flanges, means for securing one of said end flanges to said torque collar, and means for securing the other end flange to the second spider, there being a series of elongated slots formed in the medial regions of said torque collar providing intervening torque struts extending between said end flanges.

12. A reel assembly for printing presses comprising a central supporting shaft mounted for rotation about a horizontal axis, a key fitted to said shaft and substantially coextensive therewith, first and second metallic spiders each having a plurality of radially extending supporting arms formed thereon mounted on said shaft at opposite ends thereof and having keyways designed for reception of said key therein, said arms being arranged in substantially aligned pairs, a plurality of roll supporting elements adapted to receive paper rolls thereon carried at the outer ends of said arms, means for applying torque to one end of the shaft to index the shaft and move the roll supporting elements successively through loading, reserve and feeding positions, set screws extending through the metal of said first spider and engaging the opposite sides of said key, the keyway in said second spider being substantially wider than the width of said key to provide clearance portions on opposite sides of the key, a metallic torque collar mounted on said shaft adjacent said second

spider and having a keyway therein for reception of said key, set screws extending through the metal of said torque collar and engaging said key on opposite sides thereof, and elastic means connecting said torque collar and second spider.

13. A reel assembly comprising in combination, a central supporting shaft mounted for rotation about a horizontal axis, a driving gear on one end of said shaft, a first spider mounted on said shaft adjacent said gear, a second spider fixedly mounted on said shaft at the end thereof remote from said gear, elastic coupling means for limiting rotational movement of said first spider relative to the shaft, and a plurality of paper roll supporting elements supported by said spiders in spaced relationship.

14. In a reel assembly for printing presses, a central supporting shaft mounted for rotation about a horizontal axis, a driving gear mounted on one end of said shaft, a first spider mounted on said shaft adjacent said driving gear, a second spider mounted on said shaft adjacent the end thereof remote from said gear, a key secured to said shaft and substantially coextensive therewith, said key being secured to said second spider to fixedly connect the latter to said shaft and prevent relative rotation between said latter spider and shaft, there being a clearance space formed in said first spider for said key permitting limited rotational movement of the spider relative to said shaft, an elastic coupling connecting said first spider and shaft and restraining rotational movement of the spider relative to said shaft, and a plurality of paper roll supporting elements supported by said spiders.

15. In a reel for supporting a plurality of web rolls for a printing press, the combination comprising a rotatably mounted horizontal shaft, first supporting means connected to said shaft and having a plurality of first roll center supporting elements spaced about said shaft for rotatably supporting one end of each web roll, indexing means connected to said shaft at a point spaced therealong from said first supporting means for rotating said shaft to bring each roll in succession into a predetermined position in which the roll will be unwound, second supporting means connected to said shaft and having a plurality of second roll center supporting elements spaced about said shaft for supporting the other end of each roll, said second supporting means being disposed along said shaft between said first supporting means and said indexing means, said first supporting means being subject to varying torsional deflection relative to said indexing means as said shaft is rotated and the rolls are unwound, said torsional deflection resulting in lateral deflection of said first roll center supporting elements about the axis of said shaft, and said second supporting means including spring means interposed between said second roll center supporting elements and said shaft to provide for lateral deflection of said second roll center supporting elements about the axis of said shaft by an amount corresponding generally to said lateral deflection of said first roll center supporting elements to avoid misalignment between said first and second roll center supporting elements.

16. In a reel for supporting a plurality of web rolls for a printing press, the combination comprising a rotatably mounted horizontal shaft, first supporting means including a first spider and means for connecting said spider to said

shaft, said spider having a plurality of first roll center supporting elements spaced about said shaft for rotatably supporting one end of each web roll, indexing means connected to said shaft at a point spaced from said first spider for rotat-
ing said shaft to bring each roll in succession into a predetermined position in which the roll will be unwound, second supporting means includ-
ing coupled means consisting of a second spider and means for connecting said second spider to said shaft, said second spider being disposed along said shaft between said first spider and said indexing means and having a plurality of second roll center supporting elements for sup-
porting the other end of each roll, said first sup-
porting means being subject to varying torsional deflection relative to said indexing means under the weight of said rolls as said shaft is rotated and said rolls are unwound, said tor-
sional deflection resulting in lateral deflection of said first roll center supporting elements about the axis of said shaft, and one of said coupled means including spring means interposed between said second roll center supporting ele-
ments and said shaft to provide for lateral deflection of said second roll center supporting ele-
ments about the axis of said shaft by an amount corresponding generally to said lateral deflection of said first roll center supporting elements so as to avoid misalignment between said first and second roll center supporting elements.

17. In a reel for supporting a plurality of web rolls for a printing press, the combination comprising a rotatably mounted horizontal shaft, supporting means connected to said shaft and having a plurality of first roll center supporting elements spaced about said shaft for rotat-
ably supporting one end of each web roll, indexing means connected to said shaft at a point spaced therealong from said supporting means for rotating said shaft to bring each roll in succession into a predetermined position in which the roll will be unwound, a spider connected to said shaft at a point therealong between said supporting means and said indexing means and having a plurality of second roll center supporting elements spaced about said shaft for sup-
porting the other end of each roll, said supporting means being subject to varying torsional deflection relative to said indexing means as said shaft is rotated and the rolls are unwound, said torsional deflection resulting in lateral deflection of said first roll center supporting elements about the axis of said shaft, a portion of said lateral deflection being due to the torsional deflection of the portion of said shaft extending between said supporting means and said spider, and said spider including spring means in the form of a plurality of thin flexible generally radial spring arms on said spider and supporting said second roll center supporting elements to provide for lateral deflection thereof by an amount corre-
sponding generally to said lateral deflection of said first roll center supporting elements to com-
pensate for said torsional deflection of the por-
tion of said shaft extending between said sup-
porting means and said spider and thereby avoid misalignment between said first and second roll center supporting elements.

18. In a reel for supporting a plurality of web 70 rolls for a printing press, the combination comprising a rotatably mounted horizontal shaft, a substantially rigid first spider adjustably mov-

able along said shaft and having a plurality of first roll center supporting elements spaced about said shaft for rotatably supporting one end of each web roll, means for releasably securing said first spider to said shaft, indexing means connected to said shaft at a point spaced therealong from said first spider for rotating said shaft to bring each roll in succession into a predetermined position in which the roll will be unwound, a second spider adjustably movable along said shaft between said first spider and said indexing means and having a plurality of second roll center sup-
porting elements spaced about said shaft for sup-
porting the other end of each roll, means for releasably securing said second spider to said shaft, said first spider being subject to varying torsional deflection relative to said indexing means as said shaft is rotated and the rolls are unwound, said torsional deflection being largely due to the torsional elasticity of said shaft, said torsional deflection resulting in lateral deflection of said first roll center supporting elements about the axis of said shaft, and said second spider includ-
ing spring means in the form of a plurality of thin flexible generally radial spring arms on said second spider and supporting said second roll center supporting elements to compensate for the torsional deflection of the portion of said shaft between said first and second spiders for a predetermined spacing between said spiders and thereby equalize the lateral deflections of said first and second roll center supporting elements to avoid misalignment therebetween.

19. In a reel for supporting a plurality of web 35 rolls for a printing press, the combination comprising rotatable indexing means, first supporting means coaxial with said indexing means and having a plurality of first roll center supporting means spaced around the rotary axis of said indexing means for supporting one end of each web roll, means for connecting said first support-
ing means to said indexing means, second sup-
porting means coaxial with and connected to said indexing means and having a plurality of second roll center supporting means spaced around the rotary axis of said indexing means for support-
ing the opposite ends of said rolls, said indexing means having means for rotating said first and second supporting means to bring the rolls suc-
cessively into a predetermined position in which the web rolls will be unwound, said first support-
ing means being subject to torsional deflection under the weight of said rolls as said first and second supporting means are rotated and the rolls are unwound, said torsional deflection re-
sulting in lateral deflection of said first roll center supporting means, and said second supporting means having resilient means interposed between said second roll center supporting means and said indexing means to provide for lateral deflection of said second roll center supporting means by an amount corresponding generally to said lateral deflection of said first roll center supporting means to avoid misalignment of said first and second roll center supporting means.

HENRY L. McWHORTER.
